CLAIM

The ornamental design for the gas nozzle holder, as shown and described.

DESCRIPTION

FIG. 1 is a front elevational view of the gas nozzle holder showing my new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof; and,

FIG. 7 is a front elevational view at a reduced scale showing the claimed article in use.

The broken line showing of the words in FIG. 1 and the fragmented gas pump trigger in FIG. 7 is for environmental purposes and forms no part of the claimed design.
